UNITED STATES PATENT OFFICE.

HAVARD F. HUDSON, OF WICHITA, KANSAS.

RADIATOR PROTECTOR.

Application filed March 25, 1926. Serial No. 97,246.

This invention relates to improvements in 5 radiator protectors and has reference more particularly to improvements in that particular type of radiator protector described and claimed in United States Letters Patent No. 1,489,531 granted to me on April 8, 1924.

Radiator protectors of the type to which this invention relates are intended to be applied to the automobile radiators in winter and times of cold weather. They are nearly all provided with pivoted louvers that can be moved from closed to open position and vice versa. When the engine is cold or is 10 standing still the louvers should be in their closed position and should remain closed until the engine and radiator warm up when they should slowly and gradually open and remain open or partly open as long as the 15 engine is running. As soon as the engine stops the louvers should close at once so as to conserve the heat. It is also desirable that the louvers shall partly close when the speed of the engine is reduced, as for example, when the engine is idling as less 20 heat is then being generated and therefore less air is necessary to keep the parts cool.

I am aware that it is old to provide radiator protectors, of the type here under 25 consideration, with thermostats that open and close the louvers in accordance with the temperature. All of such thermostatically controlled protectors, with which I am familiar, however, have this objectionable feature 30 that they keep the louvers in open position for some time after the engine stops and close them slowly only as the engine cools and close them completely only after the engine and associated parts become quite 35 cold. When a radiator is provided with a protector whose louvers are opened and closed by a thermostatic motor and the car is operated intermittently on a cold day, it is obvious that each time the engine is 40 stopped the protector remains open until the parts get cold with the result that the engine is always cold when it is again started. It is obvious that more satisfactory 45 thermal conditions would prevail if the protector were so constructed that it would automatically close whenever the engine ceased functioning so as to trap the heat and conserve it as much as possible and it is to the 50 production of such a protector that my present invention relates.

In order to describe my invention so that

the construction and operation thereof can be readily understood, I shall have reference to the accompanying drawing in which the present preferred embodiment thereof has been illustrated and in which:

Fig. 1 is a side elevation of an automobile water cooling radiator and a portion of the engine, a protector being attached to the front of the radiator and shown in section; 65

Fig. 2 is a section taken on line 2—2, Fig. 1, portions being broken away to better disclose the construction;

Fig. 3 is a section taken on line 3—3, Fig. 2; 70

Fig. 4 is a section taken on line 4—4, Fig. 3;

Fig. 5 is a view looking in the direction of the arrow 5 in Fig. 1 and shows a plan view of the bracket that supports the 75 motor;

Fig. 6 is a view of the wind motor wheel looking in the direction of the arrow 6 in Fig. 1; and

Fig. 7 is a section similar to that illustrated in Fig. 3 but showing a modified construction comprising a thermostatically controlled stop. 80

Numeral 1 represents a radiator such as is almost universally employed on automobiles for reducing the temperature of the cooling water. Employed in connection with the internal combustion engine 2 is a fan 3 that is driven from the crank shaft of the motor by means of a belt 4 or other equivalent means. 85 The parts just mentioned are present in all water cooled automobile power plants and have been shown merely so as to enable the invention that forms the subject matter of this application to be properly explained. 90

I have already pointed out that it is customary to provide automobile radiators with a protector that can be secured to the same and which has a plurality of louvers that are movable about parallel pivots from open to closed position and vice versa. In the drawing reference numeral 5 represents the vertical sides and numeral 6 the horizontal sides of boxing or casing which is also provided with outwardly extending flanges 7 which are adapted to fit against the face of the radiator; these flanges have openings 8 for the reception of bolts by means of which the casing is secured to the radiator. The outer surface of the casing has a rectangular opening bounded by the edges of the inturned flanges 9. A plurality of louvers 10 have 100

105

110

their ends hingedly connected with the vertical flanges 9 by means of hinges 11 and are so spaced that when they occupy their normal positions in substantially vertical planes, 5 the lower edge of one louver contacts with the upper edge of the louver below so as to close the rectangular opening. When the louvers are rotated about their pivots towards the positions shown in Figs. 1 and 3, they continually increase the effective area through which air may flow. I have shown these louvers hinged so as to rotate about their upper edges but this is not necessary as they may be hinged so as to rotate about axes that are located at their upper edges or any point intermediate the upper and lower edges but the arrangement shown is considered to be the preferable one. In order that all of the louvers may move simultaneously and to the same extent, the free edge of each is interconnected with the corresponding free edge of the other by means of a rod 12 that is pivotally connected with each louver by means of a pin 13. In the construction 25 shown the action of gravity tends to move the louvers 10 to closed position; it is preferable, however, to assist the closing force exerted by the action of gravity and this can be done by means of springs. The spring 30 that has been designated by numeral 14 has its upper end attached to a bracket 15 that has been shown as being attached to the upper louver, while the lower end is secured to a straight threaded portion 16 that passes 35 through the lower horizontal side 6 and is provided with a nut 17 by means of which the tension may be adjusted. Spring 14 is preferably somewhat weak and is so adjusted that it is under tension in all positions 40 of the louvers and therefore exerts a continuous force tending to close the louvers. It is sometimes desirable to add a second spring 18 whose upper end is attached to the upper louver by means of a bracket 19 and has its 45 lower end secured to the straight threaded part 20 which has associated with it an adjusting nut 21. Spring 18 may be made of stiffer material than spring 14 and is so adjusted that it is not put under tension until 50 after the louvers 10 have opened to a considerable extent; this is accomplished by locating the nut 21 in such a position that it does not come into contact with the side 6 until after the louvers have been moved from 55 closed towards open position.

It is evident from the description given above that unless the louvers 10 are acted upon by some other force they will remain closed. As long as the louvers remain in 60 closed position, air cannot flow through the radiator and the radiation effect is therefore at a minimum. When the engine is standing still it is, of course, desirable that the louvers shall be closed for if they are open or partly open the heat will be dissipated at

a greater rate. It is understood, of course, that protectors, like the one here under consideration, are employed mostly in cold weather but may be used all year if desired.

When the engine is first started it is 70 naturally cold and does not operate satisfactorily. It is desirable to bring the engine and cooling water to the optimum temperature as soon as possible and therefore the louvers should be retained closed until the 75 engine has attained a temperature that permits it to operate satisfactorily after which the louvers should gradually open so as to prevent the parts from becoming too hot and I will now describe the mechanism by 80 which this is accomplished.

In the patent, above identified, I have shown, described and claimed a thermally responsive element comprising a wax-like substance which is associated with proper 85 mechanical means for holding the louvers in closed position until the wax has reached a sufficient temperature to become viscous when the louvers will be permitted to move slowly towards open position. In Figs. 1, 2, 3 and 90 4, I have shown such a means which in the instant case consists of closed casing 22 provided with a fill opening 23 that is closed by means of a vented cap 24. This casing 95 is secured to the rear surface of the upper flange 9 by means of a bracket 25 and carries a rotatable shaft 26 which carries a fan-like structure 27 that is nonrotatably secured to it. A ratchet wheel 28 is secured to the shaft 26 outside of the casing. A 100 lever arm 29 has one end pivotally secured to the shaft 26 and the other end pivoted at 30 to the upper end of the connecting rod 31 whose lower end is pivoted at 32, to the upper end of the rod 12. A pawl 33 is pivoted to the arm 29 and cooperates with the teeth of the ratchet wheel in the manner clearly shown in Figs. 1 and 3. The interior of the casing 22 is partly filled with a resinous wax 34 that when cold resembles 105 sealing wax but which softens when heated so as to become gummy and viscous and finally quite fluid. It is evident that the shaft 26 and attached fan structure 27 cannot be rotated as long as the wax 34 is cold but can be rotated by the application of considerable force as soon as the wax softens and becomes gummy and with less force and more quickly when the wax has been thoroughly heated. The wax may be made 110 from viscous oil and resin and the proportions are selected with due regard to the temperature at which the wax is to soften which temperature should correspond to the proper working temperature of the engine. 115 Since the pawl 33 is effective only when the rod 12 tends to move upwardly, it is evident that the control device can interpose no resistance to a closing movement of the louvers but resists the opening movement only. 120

As explained above it is the object of this invention to produce a radiator protector that will close immediately upon stopping of the motor and open only after the parts have become properly heated. To accomplish this result it is necessary to provide means that becomes effective when the motor operates for producing a force that can be utilized for opening the louvers and which become inoperative as soon as the engine stops so that the combined action of gravity and the springs 14 and 18 may move the louvers to closed position as soon as the engine has stopped. Such a force may be obtained in a variety of different ways as by utilizing the partial vacuum in the intake manifold, the pressure in the exhaust manifold, the current produced by the generator or the air flow produced by the cooling fan, in short any means that depends on the operation of the engine in such a way that it is effective only when the engine is running and exerts no power while the engine is stationary. As an example of one means for obtaining the desired force to open the louvers, I have shown a small fan or windmill wheel which has been indicated in its entirety by the reference numeral 35 and which may be constructed in any suitable manner but which has been shown as formed from a circular sheet of metal that has been cut radially so as to form a plurality of vanes 36 that radiate from the central portion 37 and which are twisted into a propeller shape and have their corresponding inner corners secured to a circular ring 38 (Fig. 6). The wheel 35 is nonrotatably secured to the outer end of the shaft 39. In Fig. 5 I have shown a supporting structure or bracket 40 that has been shown as formed from two pieces of sheet metal one of which has a straight portion 41 from one side of which an arm 42 projects. This arm extends outwardly at right angles to the plane of the part 21 and is provided with an opening 43 through which the bolt 44 (Fig. 1) may pass so as to clamp it to the engine. A flat V-shaped member 45 is secured to the ends of the part 41 by rivets 46, or by any other suitable means, and forms with it a rectangle. The shaft 31 is rotatably mounted in the bearings 47 and 48. The end 49 of the part 45 is perforated for the reception of a tube 50 that extends forwardly and terminates at a point 50^a in front of the radiator, a fine wire, cable, cord or catgut line 51 has one end secured to the shaft 39 and passes through the tube 50; the other end being connected with one end of the spring 52 whose other end is connected with the free edge of one of the louvers 10. Assuming now that the louvers occupy their closed position and assuming further that the wax 34 is hot and soft, let us consider a case in which the engine has just been started. The fan 3 will be rotated and direct a breeze onto the wheel 35 which will begin rotating whereby the line 51 will be wound onto the shaft 39 in the manner shown in Fig. 5; as soon as the line 51 is put under tension it will tend to open the louvers and unless the opening is resisted by the action of the wax, the force produced by the rotation of the wheel 35 will move the louvers to the wide open position shown in Fig. 3 in which position both of the springs 14 and 18 will be under tension. If the engine is slowed down, as, for example, when idling the fan 3 will rotate slower and the decreased velocity of the breeze that strikes the fan wheel 35 will not produce sufficient torque to overcome the action of the forces that tend to close the louvers and they will therefore move towards closing position. As the louvers move towards closing position, the force exerted by the springs 14 and 18 will decrease until equilibrium will be established between the opening force produced by the wheel 35 and the closing forces at which point the louvers will come to a stop. If the engine is stopped, the wheel 35 will exert no force and the louvers will close immediately. If the engine is started before the wax 34 cools, the louvers will be promptly opened by the action of the wheel 35. If on the other hand, the engine is stopped and permitted to remain stationary until the wax 34 cools and hardens, then when the engine is again started the pawl 29 will be forced against one of the teeth of the ratchet wheel 28 by the action of the force produced by the wheel 35, but since the wax is hard, the wheel 28 will be held against rotation and acts as a stop thereby preventing the louvers from opening. As soon as the radiator gets sufficiently hot, the wax contained in the casing 22 will soften and permit the paddle wheel 27 to rotate thereby allowing the louvers to open. If the louvers should open so wide that the amount of air that is permitted to flow through the radiator reduces the temperature to such an extent that the wax cools and hardens, then whenever the engine is slowed down, the louvers will move towards closed position and will be held against opening movement by the pawl 29. If the opening is still too great, then when the engine is again slowed down, the louvers will close still more until the proper opening is obtained for maintaining the desired temperature. Whenever the engine is stopped, the louvers immediately close.

Results analogous to those described may be obtained by means employing a thermostatically controlled stop instead of the control box containing the wax and an example of such a construction has been shown in Fig. 7 where the control box 22 connecting rod 31 and associated parts have been replaced by a hinged stop member 53 that has

one end pivoted at 54. A thermostat 55 is secured to the casing by some suitable means such as brackets 56 and is connected to the stop 53 by some intermediate mechanism 5 such as a bell crank 57 and a connecting rod 58 so that the stop 53 will be rotated counterclockwise as the temperature increases. The position of the louvers will then be determined by the position of the 10 stop 53 and this in turn will be controlled by the thermostat that in turn is governed by the temperature. It will be noted that the stop does not in any way interfere with the closing of the louvers but merely determines 15 the extent to which they may be opened. When the engine is cold the stop 53 prevents the louvers from opening and as the temperature increases it moves counterclockwise until the temperature becomes stationary. By properly proportioning the 20 opening force and the force exerted by the thermostat, the latter can be made to close the louvers in opposition to the opening force and will therefore serve to regulate 25 the opening of the louvers to the extent required to obtain the proper temperature.

The force exerted by the wheel 35 may be regulated by properly proportioning the diameter of the shaft 39 at the place where 30 the line 51 is coiled about it or by the well known method of reducing gears.

It is evident that the wind motor represented by wheel 35 does not necessarily have to be placed to the rear of the fan in the 35 manner shown but that it may, if desired, be put in front of the radiator and even in front of the louvers or it may be built into the protector so as to form a unitary assembly. It should also be understood that any 40 type of wind motor wheel may be used and that it is merely essential that the motor should depend on the operation of the engine for its power so that it will exert a force tending to open the louvers only while 45 the engine is running.

In both of the embodiments shown and described, the thermostatic control device merely opposes the opening of the louvers but does not in any way interfere with the 50 closing which can therefore take place as soon as the engine stops and without waiting for it to cool.

Having now described my invention what is claimed as new is:

55 1. A device for controlling the flow of air through a radiator associated with an internal combustion engine, comprising in combination, a casing adapted to be secured

to the radiator, said casing having an opening, a plurality of louvers hingedly connected to the casing and arranged to be moved into and out of closed position so as to control the effective area of the opening in the casing, means comprising two springs of unequal strength for producing a force tending to move the louvers to closed position, the weaker of said springs being constantly under tension whereas the stronger of said springs is put under tension only after the louvers have been opened to some extent, means comprising a rotatable motor for producing a force tending to move the louvers to open position, said last named means being so associated with the internal combustion engine that it is operative only when the engine operates and means responsive to temperature conditions of the engine for controlling the opening of the louvers.

2. In a power plant comprising an internal combustion engine, having a cooling system including a radiator and a fan for forcing air through the radiator, a casing adapted to be secured to the front of the radiator, said casing having an opening, a plurality of louvers hingedly connected to the casing and adapted to be moved into position to close said opening, means associated with said louvers and casing for producing a force tending to close the opening in the casing and means comprising a wind wheel for producing a force tending to move the louvers to open position, said wheel receiving its power from the breeze produced by the fan whereby the wheel is operative only when the fan operates.

3. In a power plant comprising an internal combustion engine, having a cooling system including a radiator and a fan for forcing air through the radiator, a casing adapted to be secured to the front of the radiator, said casing having an opening, a plurality of louvers hingedly connected to the casing and adapted to be moved into position to close said opening, means associated with said louvers and casing for producing a force tending to close the opening in the casing and means comprising an air operated motor for producing a force tending to move the louvers to open position, said motor receiving its power from the breeze produced by the fan whereby it is operative only when the fan operates.

In testimony whereof I affix my signature.
